FRANK H. TREGO, OF SPRINGFIELD, MASSACHUSETTS.

LUBRICATING-PUMP FOR ENGINES.

,174,779.

Specification of Letters Patent

Patented Mar. 7, 1916.

Application filed June 23, 1915. Serial No. 35,844.

to all whom it may concern:

Be it known that I, FRANK H. TREGO, a citizen of the United States, and a resident of Springfield, in the county of Hampden and State of Massachusetts, have invented a new and Improved Lubricating-Pump for Engines, of which the following is a full, clear, and exact description.

This invention relates to pumps designed for use in forced lubricating systems for engines, and it has for its general objects to provide a special form of pump that is mounted in the crank case of the engine, the pump being so designed as to be readily removable or assembled, of durable and substantial construction and requiring comparatively little power for its operation.

A further object of the invention is the provision of a pump which is mounted on the bottom of the crank case in such a manner as to be readily removable, the pump being surrounded by a screen which is inserted upwardly into the crank case through an opening in the bottom, and the bottom of the screen is provided with a plate which is bolted to the bottom of the crank case to form a closure for the said opening.

Another object of the invention is to provide a pump which is fastened to the upper section of the crank case and is driven from the cam shaft of the engine by a suitable driving connection which is so designed that the pump can be readily assembled or disassembled without the necessity of taking the crank case apart, and in the upper section of the crank case is an outlet conduit which communicates with the discharge passage of the pump.

With these objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference indicate corresponding parts in all the views, Figure 1 is a sectional view of the pump and its operating means mounted in a crank case, the section being taken on the line 1—1, Fig. 3; Fig. 2 is a sectional view on the line 2—2, Fig. 3; Fig. 3 is a horizontal section on the line 3—3, Fig. 1; and Fig.

4 is a horizontal section on the line 4—4, Fig. 1.

Referring to the drawing, A designates the upper section of a crank casing, and B the bottom of the lower section, and mounted between these sections is a lubricating pump C of the cog gear type. This pump comprises a casing formed of an upper body section 1 and a lower bottom section 2 which are detachably connected by screws or equivalent means 3, the said casing being formed with a chamber 4 which contains the intermeshing gears 5 and 6, the teeth of which coöperate with the walls 7 to carry oil from the inlet port 8 to the discharge passage 9. The casing of the pump has an upwardly-extending web 10 that depends from the under side of a plate 11, which is removably secured to the upper section A of the crank case. Between the plate 11 and the pump casing is a conduit 12 that forms the discharge passage for the pump. The casing section 1, the web 10, plate 11 and conduit 12 may be a single casting. The sections 1 and 2 of the pump casing have bearings 13, 13' and 14, 14' for the shafts 15 and 16, respectively, on the gears 5 and 6. The shaft 15 extends upwardly through openings 17 and 18 in the plate 11 and bottom 19 of the crank case section A and is operatively connected with suitable driving means.

The oil is filtered before it enters the pump, the filtering means being a surrounding screen D which is supported on and arranged within a cage E, which may be a casting or other structure of suitable form. This cage is insertable through an opening 20 in the crank case, and it has its bottom so constructed as to form a plate 21 which closes the opening, the plate being secured to the bottom of the crank case by bolts or equivalent means 22, and at this joint fluid-tightness is obtained by a gasket 23. The under side of the plate 11 of the pump structure has a groove 24 into which is set a felt or other packing 25 with which the top of the cage engages so as to prevent sediment from being thrown into the strainer D. The bottoms of the ports e in the cage are located slightly above the bottom of the crank case so that sediment in the oil will have a chance to collect and not clog the screen D.

The pump is operated from the engine cam shaft 26 mounted in the usual manner

in the upper section of the crank case, and a skew gear 27 thereon meshes with a skew gear 28 on the upper end of the shaft 15. A vertical bearing 29 is provided in the upper section of the crank case, and arranged therein is a bushing 30 through which the shaft 15 extends. This bushing has its upper surface countersunk so as to receive a ballbearing 31 interposed between the bushing 30 and the gear 28. This gear 28 has a squared opening into which the squared end 32 on the shaft 15 extends, and the fit is such that when the pump structure is disconnected, the shaft 15 will slip downwardly out of the gear 28 which rests on the ballbearing 31, which is in turn held by the bushing 30. An opening 33 is provided in the top of the crank case and this opening is normally closed by a cap 34 which is in such close proximity to the gear 28 as to prevent the latter from disconnecting from the pump shaft 15, and by means of the opening 33 the fingers can be inserted to centralize the gear 28 with respect to the shaft 15 when the pump is being installed. The bearing 29 is supported by a web 35 which forms a cup 36 to catch oil which is thrown off by the moving parts in the crank case, and from this cup the oil drains to the bushing 30 for lubricating the shaft. In the upper section of the crank case is a web 37 which has cast therein a distribution pipe 38 through which lubricant is forced to supply the various parts of the engine, and in the web is drilled a passage 39 lined with a steel tube 40 which communicates at its lower end with the discharge passage 9 of the pump, and which communicates with the cutlet pipe 38. By hanging the pump in the upper half of the crank casing, pipe connections which are usually in the upper and lower halves of the crank casing are eliminated, such pipe connections being substituted by the conduits 9, 39 and 40.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. The combination of an engine crank case with a lubricating pump mounted therein, said case having an opening in its bottom through which the pump is removable, and a closure for the said opening.

2. The combination of an engine crank case with a lubricating pump mounted therein, said case having an opening in its bottom through which the pump is removable, and a screen surrounding the pump and having a bottom portion forming a closure for the said opening. 70

3. The combination of an engine crank case composed of upper and lower sections, a lubricating pump mounted in the lower section and removably secured to the upper section, and a screen surrounding the pump. 75

4. The combination of an engine crank case composed of upper and lower sections, a pump removably mounted on the upper section and depending therefrom, there being an opening in the lower section through which the pump is insertible and removable, and a closure for the said opening. 80

5. The combination of an engine crank case composed of upper and lower sections, a pump removably mounted on the upper section and depending therefrom, there being an opening in the lower section through which the pump is insertible and removable, 90 and a screen surrounding the pump and supported by the lower section and forming a closure for the opening thereof.

6. The combination of an engine crank case, a lubricating pump mounted therein and formed with a top plate, the bottom of the casing having an opening, a screen surrounding the pump and removable through the said opening, the top of the screen being clamped to the top plate of the latter, and means for closing the opening of the casing. 95

7. The combination of an engine crank case, a pump in the bottom thereof, a screen surrounding the pump, the bottom of the case having an opening through which the pump and screen are removable, said pump and screen being separately fastened to different parts of the crank case, and means for driving the pump. 105

8. The combination of an engine crank case, a pump structure mounted therein and comprising a casing, a plate disposed above and connected with the pump casing, a discharge conduit between the plate and pump casing, a screen surrounding the pump structure, a packing between the top of the screen and plate of the pump structure, means for securing the pump structure in the crank case, and means for securing the screen in the crank case. 110

9. The combination of an engine crank case comprising upper and lower sections, a pump disposed in the lower section, and driving means mounted in the upper section, said pump including a shaft detachably connected with the driving means. 115

10. The combination of an engine crank case comprising upper and lower sections, the lower section having an opening, a lubricating pump insertible through the said 130

- opening and fastened to the upper section, said pump including a shaft extending into the upper section, a gear in the upper section with which the shaft engages or disengages during the installing or removing of the pump, a gear meshing with the first-mentioned gear, and means for driving the second gear.
11. The combination of an engine crank case comprising upper and lower sections, the lower section having an opening, a lubricating pump insertible through the said opening and fastened to the upper section, said pump including a shaft extending into the upper section, a gear in the upper section with which the shaft engages or disengages during the installing or removing of the pump, a gear meshing with the first-mentioned gear, means for driving the second gear, a bearing in the upper section for the said shaft, a cup adjacent the bearing to catch lubricant, and means for feeding lubricant from the cup to the bearing.
12. The combination of an engine crank case comprising upper and lower sections, the lower section having an opening, a lubricating pump insertible through the said opening and fastened to the upper section, said pump including a shaft extending into the upper section, a gear in the upper section with which the shaft engages or disengages during the installing or removing of the pump, a gear meshing with the first-men-
- tioned gear, means for driving the second gear, a bearing in the upper section for the 35 said shaft, a bushing in the said bearing having an upper countersunk surface, and a ballbearing set into the bushing and supporting the first-mentioned gear.
13. The combination of an engine crank case comprising upper and lower sections, a lubricating pump mounted in the lower section and secured to the upper section and having a discharge passage, the upper section including a web having an outlet passage 45 registering with the discharge passage of the pump, and means in the upper section for operating the pump.
14. The combination of an engine crank case comprising upper and lower sections, a lubricating pump mounted in the lower section and secured to the upper section and having a discharge passage, the upper section including a web having an outlet passage 50 registering with the discharge passage of the pump, means in the upper section for operating the pump, and a screen surrounding the pump and its discharge passage.
- In testimony whereof I have signed my name to this specification in the presence of 55 two subscribing witnesses.
